UNITED STATES PATENT OFFICE.

GUY G. MELLEM, OF MINNEAPOLIS, MINNESOTA.

DOORSTOP.

Application filed July 8, 1927. Serial No. 204,807.

My invention relates to door stops and has for its object to provide a device by means of which a swinging door may be held open regardless of its position relative to the door frame.

An object of the invention resides in providing a mounting having a transverse hole forming a bearing therein and to further provide a rod formed with an angular portion adapted to extend through said bearing and being journaled therein.

Another object of the invention resides in providing a keeper for holding said rod when said door stop is in disuse, said rod being adapted upon lateral movement to be engaged or disengaged from said keeper.

A still further object of the invention resides in enlarging one or both ends of the hole in said mounting to permit the angular portion of said rod to move within said hole in such a manner as to allow of the lateral movement of said rod in engaging or becoming disengaged from said keeper.

A feature of the invention resides in providing an angle plate adapted to abut against the angular portion of said rod to hold the same within said bearing.

With the foregoing and other objects in view, which will appear in the following description, the invention resides in the novel combination and arrangement of parts and in the details of construction hereinafter described and claimed.

In the drawings:

Fig. 1 is a perspective view of a portion of a door and door frame illustrating the application of my invention thereto.

Fig. 2 is an elevational view of the door proper illustrating the door stop in its retracted position.

Fig. 3 is an end view of the mounting forming a portion of my invention illustrating the enlargement of the bearing hole at the end thereof.

For the purpose of illustrating the application of my invention I have shown a door frame A consisting of a jamb 10 formed with vertical frame members 11 and 12 and including a threshold 13. In this frame is hung a door B formed with stiles 13 and 14 and rails 15 having mounted therein a panel 16. Door B is swingably mounted in the frame A by means of hinges 17 and is adapted to swing outwardly as shown in Fig. 1, to pass over the ground designated at 18.

The invention proper consists of a rod 19

which is swingably mounted in a mounting 20 adapted to be attached to the stile 14 of the door B. This mounting is preferably struck out of sheet metal and is formed with a wing-like portion 21 providing a body for the device. The end of the body portion 21 is looped or bent as indicated at 22 to form a hinge or an elongated eye having a circular opening passing completely through the same. This portion of the device forms a bearing which is arranged to receive a portion 23 of the rod 19 which is bent outwardly therefrom at right angles and forms a pintle for swingably supporting said rod. The mounting 20 may be attached to the stile 14 by means of screws 24 best shown in Fig. 2.

The operation of the device is as follows: The rod 19 is constructed somewhat longer than the distance from the bearing 22 to the ground 18 immediately below the lower portion of the door, so that when the door is swung open said rod 19 occupies an angular position such as shown in Fig. 1 with the lower end 25 of said rod directly engaging the ground. Movement of the door B towards the frame A is hence prevented through the engagement of the rod 19 with the ground so that the door is at all times prevented from further closing. It will be noted that the wing-like portion 21 of the mounting 20 extends towards the ground which brings the closed portion of the hinge eye 22 in contact with the bent portion 23 of rod 19 when the device is brought into action, thereby presenting a suitable bearing capable of resisting the thrust from the rod 19 when resisting the closing of the door. To prevent the penetration of the end 25 of rod 19 into the ground 18, the end of said rod is arranged with a transverse pin 26 which extends completely across the same and serves as a shoulder or abutment to the end of the rod as clearly shown in Fig. 1.

For the purpose of holding the rod 19 while in disuse, I provide a keeper 27 which is secured at one end to the stile 14 of the door B by means of screws 28 at a location considerably above the mounting 20. This keeper consists of a strip of spring metal formed with a groove portion 29 near its free end behind which the said rod 19 may lie when in its retracted position and is further arranged with an upturned end 30 to facilitate the insertion of said rod behind the same. It hence becomes evident that by moving the said rod 19 laterally after the same has been swung

into its uppermost position, the said rod may be moved into engagement or moved out of engagement with said keeper by simply shifting the rod laterally with one hand and without manipulating the keeper with the other hand. To accommodate such movement the hinge 22 formed on the mounting 20 is constructed with the extreme ends 31 thereof bent outwardly therefrom to make 10 the hole indicated at 32 passing through said hinge enlarged at its two ends. This permits the pintle 23 within said bearing to rock, as indicated in dotted lines in Fig. 2 to allow the rod 19 to be shifted a sufficient amount 15 laterally to permit of insertion beneath of the keeper 27 or permit of its removal therefrom.

For the purpose of holding the pintle 23 of rod 19 within the bearing 22 I employ an angle plate 33 which is attached to the stile 20 14. This angle plate is constructed with a base 34 directly attached to the said stile through screws 35. Said angle plate further comprises a flange 36 of such a height that the same extends outwardly beyond the bearing 22. This angle plate is so disposed that the rod 19 may swing in between the same and the edge of the mounting 20 so as to give the same the necessary lateral movement required in inserting said rod beneath the 30 keeper 27. At the same time said angle plate prevents the pintle 23 of said rod from sliding out of the bearing 22.

The advantages of my invention are manifest. An extremely simple and effective device is provided whereby an open door may be held from accidentally closing. The device can be constructed from available stock at a nominal cost and can readily be installed without the aid of special equipment or tools. 40 The device will not readily get out of order and there are no cotter keys or other breakable parts which may break or fall apart so as to render the device inoperable.

Changes in the specific form of my invention, as herein disclosed, may be made within the scope of what is claimed without departing from the spirit of my invention.

Having described my invention, what I claim as new and desire to protect by Letters 50 Patent is:

1. A door stop comprising a mounting, said mounting being formed with a transverse bearing, a rod, a pintle formed on said rod and swingably mounted in said bearing, 55 a keeper for engagement with said rod, said rod being laterally movable for engagement with said keeper, said pintle being transversely movable within said bearing to permit of the lateral movement of said rod for 60 engagement with said keeper.

2. A door stop comprising a mounting having one end thereof bent upon itself to form a bearing, the ends of said bearing be-

ing enlarged as compared with the central portion thereof, a rod formed with a pintle at one end, said pintle passing through said bearing and being journaled therein, a keeper, said rod being engaged within said keeper through lateral movement thereof, said pintle being adapted to move at the enlarged 65 ends of said bearing to allow the lateral movement of said rod for engagement with said keeper. 70

3. A door stop comprising a mounting having a hole extending through the same to form a bearing, a rod having an angular portion issuing outwardly therefrom and adapted to extend through said hole for swingably supporting said rod relative to said mounting, and an abutment positioned adjacent the bent end of said rod for holding said angular portion of said rod within said bearing. 75

4. A door stop comprising a mounting having a hole extending through the same to form a bearing, a rod having an angular portion issuing outwardly therefrom and adapted to extend through said hole for swingably supporting said rod relative to said mounting, and an angle plate positioned adjacent the bent end of said rod for holding the angular portion of said rod within said bearing. 80

5. A door stop comprising a mounting having one end thereof bent upon itself to form a bearing, the extreme edge of said bent end approaching the unbent portion of said mounting, one end of said bearing being enlarged, a rod formed with a pintle at one end, said pintle passing through said bearing and being journaled therein, a keeper, said rod being engaged within said keeper through lateral movement thereof, said pintle being adapted to move at the enlarged end of said bearing to allow of the lateral movement of said rod for engagement with said keeper, said mounting being disposed to present the portion of said bearing away from the edge of the bent portion thereof to said pintle to resist the thrust upon said rod occasioned through the closing of the door. 95

6. A door stop comprising a mounting having a hole therethrough to form a bearing, a rod having an angular portion bent out from the same to provide a trunnion, said angular portion being free at its outer end to permit of the endwise insertion thereof into said hole and a detachable abutment adapted to be placed adjacent the bent end of said rod for holding said angular portion within said bearing. 100

In testimony whereof I have affixed my signature to this specification.

GUY G. MELLEM.
